UNITED STATES PATENT OFFICE

2,154,616

GREASE-SETTING AGENT

Torsten Hasselstrom, Savannah, Ga., assignor to
G. & A. Laboratories, Savannah, Ga., a corporation of Georgia

No Drawing. Original application March 24, 1937, Serial No. 70,671. Divided and this application August 26, 1937, Serial No. 161,165

2 Claims. (Cl. 87—9)

This invention relates to an improved detergent, wetting and grease-setting agent and process of producing the same.

Many detergents and wetting agents are known, for example, soaps, sulfonated castor oil, sulfated higher fatty alcohols, sulfonated higher fatty acids, etc. Of these, soaps suffer from the disadvantage of being precipitated from their aqueous solutions by the electrolytes in hard waters, particularly by waters carrying calcium compounds, and the sulfated alcohols of the higher fatty acids and the sulfonated higher fatty acids suffer from the disadvantage of high cost of the higher fatty alcohol used, so that their use in trade has been severely limited.

The product in accordance with my invention possesses superior detergent and wetting powers, in comparison with many of those now used in various industries, as, for example, in the manufacture of soap, the textile and tanning industries, and many others, is economical to manufacture, requires no complicated separation and isolation of the material to be sulfonated, and may be made by a very simple sulfonation process and apparatus. My product is not precipitated by calcium salts contained in hard waters, and is non-hydrolyzable by alkali or acid under practical conditions of use.

Broadly speaking my invention comprises the product of the sulfonation of pseudopimamic acid, for example, prepared in accordance with the process disclosed in application for United States Letters Patent, Serial No. 675,976, filed June 15, 1933, entitled "A new rosin acid and process of producing the same," in accordance with which rosin oil having an appreciable resin acid content, say at least about five per cent, or a product obtained from rosin by suitable heat treatment (with or without distillation), such as a rosin known in the trade as a heat-treated or partially distilled rosin, is extracted with an aqueous solution of an alkali, which is preferably caustic soda or caustic potash. The extraction is carried out preferably by thoroughly mixing the raw material and the alkaline solution in an appropriate manner, as by stirring or agitation, and is continued until practically complete saponification is accomplished. In order to break up any emulsion and to facilitate the separation of the mixture into two layers, some methanol or other suitable solvent is added just prior to the termination of the agitation. Upon standing, the mixture then separates into two layers, the upper consisting mainly of unsaponifiable material and the lower one containing the alkali pseudopimamate

in alkaline solution. This lower layer is then drawn off, acidified with a dilute mineral acid, such as hydrochloric acid or sulfuric acid, or by the addition of a suitable acid salt, such as nitre cake. This acidification precipitates the novel acid, called pseudopimamic acid, as a viscous, sticky mass, which is collected by agglomeration and then removed. It is then pressed to free it as much as possible from adhering mother liquor, and is washed thoroughly with water until substantially free from all water-soluble contaminants. The crude acid is then dried in any suitable way.

The pseudopimamic acid so produced melts at about 69—71° C., while the partially purified pseudopimamic acid melts at about 169—181° C., has an optical angle of rotation $[\alpha]_D$, of about +25° to +50°, and when more fully refined melts at 195.5 to 198° C. (corrected), has an optical angle of rotation, $[\alpha]_D$, of about +0.33° and an elementary composition which corresponds approximately to the formula $C_{20}H_{30}O_2$. As the properties of the new acid are not identical with either the abietic or the pimamic types of acids, it is called pseudopimamic acid.

More specifically my invention comprises sulfonation by treatment by concentrated sulfuric acid of pseudopimamic acid or of mixtures containing pseudopimamic acid, such, for example, as result from suitable heat-treatment of wood and/or gum rosin, if desired in a suitable solvent attacked or unattacked by concentrated sulfuric acid, e. g. carbon tetrachloride, liquid sulfur dioxide, petroleum distillates, saturated and/or unsaturated hydrocarbons, preferably of the aromatic and/or hydroaromatic series, although I may employ unsaturated aliphatic hydrocarbons, or mixtures thereof.

As sulfonating agent I preferably employ sulfuric acid of specific gravity about 1.84, although I may employ somewhat lower or somewhat higher strengths, even to fuming sulfuric acid, or chlorosulfonic acid or sulfur trioxide as the sulfonating agent.

Example I

As an example of the carrying out of my process, 50 parts by weight of partially refined pseudopimamic acid, M. P. 167—169° C.,

$$[\alpha]_D^{25} = +46.3^\circ$$

and 250 parts by weight of sulfuric acid sp. gr. 1.84 were mixed at about —5° to +5° C., stirred for about 20 minutes, then poured onto cracked ice. The brownish precipitate was filtered out,

- washed with cold water until the washings clouded when mixed with the original liquor, and the washed precipitate then extracted three times with boiling water, leaving a brownish, insoluble semi-solid resin. The hot aqueous extracts, on cooling, deposited crystalline sulfonic acid in a yield of 25.5 parts by weight, which, after repeated crystallization from glacial acetic acid, melted with decomposition at about 223-224° C.
- 10 The brownish insoluble semi-solid resin amounted to 30 parts by weight. When an acetone solution of this by-product was allowed to stand for several days, it separated a colorless, crystalline solid, which, after recrystallization from suitable solvents, melted at about 131-132° C. Instead of the partially refined pseudopimaric acid used in this example, a pseudopimaric acid of greater or less purity may be employed with consequent variation in the yields of the sulfonic acid.
- 20

Example II

- As a further example of the carrying out of my process, 1200 parts by weight of a finely pulverized product, rich in pseudopimaric acid, obtained 25 by suitable destructive distillation of wood and/or gum rosin, followed by removal of abietenes, etc., by fractional distillation under reduced pressure were mixed with 2400 parts by weight of sulfuric acid sp. gr. 1.84, and the mixture agitated for a 30 suitable time at 10-35° C., then treated as in Example I. The crude product from this reaction was extracted twice with boiling water and allowed to stand to crystallize. A sulfonic acid of lighter color than in Example I was obtained.
- 35 M. P. 223-4° C. with decomposition, $[\alpha]_D = +62.63^{\circ}$, yield 465 parts by weight, and also a dark non-crystalline sulfonic acid, whose sodium salt in aqueous solution behaved like a soap, of yield of 190 parts by weight.

40

Example III

- As a further example of the carrying out of my process, 400 parts by weight of a finely pulverized product rich in pseudopimaric acid, and obtained 45 by suitable destructive distillation of wood rosin and/or gum rosin without fractionation under reduced pressure, was treated as in Example II, giving a 10% yield of a crystalline sulfonic acid M. P. 223-4° C. with decomposition.

Example IV

As a further example of the carrying out of my process in the presence of a suitable solvent, a mixture of 100 parts of steam-distilled rosin oil, rich in pseudopimaric acid, and containing a 5 total of up to about 70% of resin acids calculated as $C_{20}H_{30}O_2$, with 200 parts of concentrated sulfuric acid of a sp. gr. of about 1.84 was agitated for a suitable length of time at a temperature of about -5° C. to about +50° C., and the crude sulfonation product so obtained worked up as in Example II.

10 My sulfonic acid product will be found variously adaptable to uses as an improved detergent and wetting out agent, e. g. in the scouring of 15 textiles, as a soap assistant, etc.

I may prepare the neutral or acid, alkali, or 20 alkaline earth salts, or salts of organic bases, e. g. of ethanolamine of my sulfonic acid product and such are also variously adaptable to uses in an improved detergent and wetting out agent.

The brownish, insoluble semi-solid resin material separated from the sulfonic acid, as shown, for example, in Example I, I have found useful 25 as a grease-setting agent, e. g. in the manufacture of cup grease, solid oils, and the like.

This application constitutes a division of my 30 application Serial No. 70,671, filed by me March 24, 1936, for Detergent and wetting agent and process of producing the same and now issued as Patent No. 2,121,032 of June 21, 1938.

What I claim and desire to protect by Letters Patent is:

1. As a grease-setting agent, the brownish, insoluble, semi-solid resin obtained by treating a material from the group consisting of pseudopimaric acid and mixtures containing pseudopimaric acid with a sulfonating agent, and removing by hot aqueous extraction the water-soluble sulfonic acid.

2. As a grease-setting agent, the brownish, insoluble, semi-solid resin obtained by treating pseudopimaric acid with sulfuric acid of density about 1.84 and removing by hot aqueous extraction the water-soluble sulfonic acid.

TORSTEN HASSELSTROM.
